MACHINE FOR APPLYING DRY TRANSFERS
OF MARKINGS

Edward E. Ziskind, New York, N. Y.

Application August 14, 1941, Serial No. 406,757

8 Claims. (Cl. 41—1)

This invention relates to new and useful improvements in machines for applying dry transfers of markings. More particularly, the invention contemplates the construction of a machine capable of applying dry transfers from an upright position.

This invention contemplates characterizing the machine by a vertical member over which various articles may be placed such as felt hats, felt bodies, straw hats, straw bodies and the like, in a way that the dry transfer may be applied to the inner top portion of the crown of the hat or hat body, or at a top location of other articles, or on the flat surface of gloves, woolen goods, linens, cotton goods, silks, and other textile mixtures, or on the flat surface of fur skins, leather skins, calling for special markings, or trade marks, or identification markings, by the pressure of the hand on the article, or by a pressure unit applied on top or over the article, thereby immediately making an imprint from the dry transfer paper to the article, under which runs the web of dry transfer paper, the printing matter facing upwards, and which web of dry transfer paper rests on heating unit.

Still further the invention proposes providing the vertical member with a heat unit mounted across the top portion thereof for supplying the necessary heat to accomplish the transferring operation.

The invention also contemplates the provision of guide means for guiding a web of dry transfer material up one side and over the top and down the other side of the vertical member.

Another object of the invention resides in the provision of means for advancing the web of dry transfer material in sections of a pre-selected length.

Still further the invention proposes to characterize the advancing means mentioned in the previous paragraph by an operator lever which may be manually operated.

In another form of the invention a certain mechanism is proposed for controlling the operator lever.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a machine for

applying dry transfers constructed in accordance with this invention.

Fig. 2 is a side elevational view of Fig. 1.

Fig. 3 is a plan view of Fig. 1.

Fig. 4 is a fragmentary horizontal sectional view taken on the line 4—4 of Fig. 2.

Fig. 5 is a sectional view of certain parts shown in Fig. 2.

Fig. 6 is a fragmentary enlarged detailed view of a portion of Fig. 2.

Fig. 7 is a horizontal enlarged sectional view taken on the line 7—7 of Fig. 2.

Fig. 8 is a side elevational view of a machine for applying transfers constructed in accordance with another form of this invention.

Fig. 9 is a fragmentary horizontal sectional view taken on the line 9—9 of Fig. 8.

Fig. 10 is another perspective view showing a portion of Fig. 8.

20 The machine for applying dry transfers, in accordance with this invention, includes a vertical member 10 over which various articles may be placed. This vertical member 10 is adapted to receive a felt hat H or other article. The crown

25 of the hat may be placed over the vertical member so that the top of the vertical member engages the inner face of the top of the crown of the hat. The vertical member 10 is substantially of inverted frusto-conical form. It is mounted on a stand 11 and preferably has several legs 12 by

30 which it may be rested on a table, bench or the like. A heat unit 13 is mounted within the interior of the vertical member 10. This heat unit projects from the top of the vertical member. At

35 this point it is provided with a heat unit 14 formed with a suitably shaped metal top, capable of effectively heating the top portion of a head section 15 mounted on the top of the vertical member. The details of the heating unit will

40 not be given in this specification as it forms no part of the invention.

45 Guide means is provided for guiding a web 16 of dry transfer material up one side and over the top and down the other side of the vertical member 10. This guide means includes a bracket 17 mounted on one side of the vertical member 10 and supports a guide roll 18 beneath which the web 16 passes. The guide means includes another bracket 19 mounted above the bracket 17 and formed with a passage 20 (see Fig. 7) through

50 which the web 16 passes. Within this passage 20, there are several blocks 21 slidably mounted upon the bracket 19. These blocks 21 are laterally adjustable. Each block is provided with an adjustment screw 22 mounted upon the bracket

19. The arrangement is such that the adjustment screws 22 may be turned in one direction or the other to advance or retract the blocks 21 so that the blocks engage the edges of the web 16 to properly guide the web.

The web 16 then continues upwards over a roller or guide bracket 23 which is mounted upon the top portion of the vertical member 10. At a point diametrically opposite the location of the roller 23 there is a similar roller 23' over which the web 16 extends. The web 16 then passes down through a bracket 19 provided with adjustably mounted blocks 21 as previously described. The web 16 then continues downwards between a pair of rollers or guide brackets 25 and 26 mounted on the bracket 21 which in turn is mounted on the side of the vertical member 10. The roller 25 carries a spring operated pawl 28 which engages a ratchet wheel 29 fixedly mounted on the bracket 21 by several rivets 30 or other similar fastening elements. The pawl 28 and ratchet are so directed that the web 16 may be freely pulled downwards, but it is restrained from moving upwards.

The web 16 comes off the supply roll 16' which is mounted on a bracket 31 projecting from the stand 11. This bracket 31 is provided with a removable screw 32 upon which the roll 16' is mounted.

Means is provided for advancing the web 16 in sections of a pre-selected length. This means includes a lever 33 which is engaged over the vertical member 10. For this reason the lever 33 has an opening 44 through which the vertical member 10 passes. The rear end of the lever 33 is pivotally mounted by a pintle 35 on the top of the stand 11. The front portion of the lever 33 is provided with an opening 36 through which the web 16 passes. A counter-pressure roller 37 is supported by a bracket 38 upon the bottom face of the lever 33 immediately adjacent the openings 36. A gripper jaw 39 is co-actable with the counter-pressure drum 37 for gripping the web 16 to move it downwards. This gripper jaw 39 has a rearwardly extending hollow stem 40 which slidably passes through a projection 41 on the bottom of the lever 33.

A rod 42 is slidably mounted in and projects from the stem 40. An expansion spring 43 is disposed within the stem 40 and normally urges the rod 42 outwards. The rear end of the rod 42 is pivotally connected with toggle members 44 and 45. The toggle member 44 is pivotally mounted on the stand 11 while the toggle member 45 is pivotally mounted on the lever 33. The adjacent ends of the toggle member are pivotally connected together by a pin 46 which passes through an opening in the rear of the rod 42. A stop member 47 has a threaded stem 48 by which it is adjustably mounted on the projection 41. This stop member 47 is capable of striking one of the legs 12 of the stand 11 for limiting the distance through which the lever 33 may be moved downwards.

Several pins 49 are mounted on the sides of the vertical member 10 and project in the path of motion of the lever 33 to limit upward motion of the lever. A spring 50 is connected between the lever 33 and the vertical member 10 and normally urges the lever into said vertical position.

The operation of the device is as follows:

An article may be placed against that portion of the web 16 which is extended across the top of the vertical member so that the dry trans-

fer is impressed on the article. Then the lever 33 may be moved downwards from its completely raised position, indicated by the dot and dash lines 33' in Fig. 2, to a bottom position in which the stop member 47 strikes the foot 12. During the early part of the downward stroke of the lever 33 the toggle members 44 and 45 move the gripper jaw 39 forwards so that the web 16 is forced against the drum 37 by which operation the web 16 is tightly gripped. During continued downward motion of the lever 33 the web 16 is drawn a distance determined by the adjustment of the stop member 47.

When the lever 33 is released it moves upwards to its top position due to the returning action of the spring 50. During the initial upward motion of the lever 33, that portion of the web 16 immediately above the gripper jaw 39 will become slack, but the rollers 25 and 26 will prevent the remaining portion of the web 16 from loosening. When the lever 33 reaches the position shown by the full lines in Fig. 2, the gripper jaw 39 will start moving free from the drum 37 which releases the web 16 so that the slackened portion now falls through the openings 36 and straightens out. The advancing means is now ready to repeat the operation.

In Figs. 8 and 9 a modification of the invention is disclosed which is similar to the prior form, except for the fact that a spring motor has been provided for moving the lever 33 downwards instead of requiring manual motion of the lever. The spring motor includes a drum 51 housing a spring 52. One end of this spring is attached by a fastening element 53 with the drum. The other end is attached by fastening elements 54 with a stem 55 which freely passes coaxially through the drum.

The drum 51 is provided with gear teeth 56 which are engaged by a spring pressed pawl 57 holding the drum 51 from normally unwinding. The spring pressed pawl 57 is mounted on a standard 58 mounted on the vertical member 10. The standard 58 also slidably supports a rack 59. Another standard 60 also mounted on the vertical member 10 assists in supporting the rack 59. A knob 61 is on the top of the rack 59 and is located at a position so that it may readily be depressed when a felt hat or any other article is pressed down upon the top of the vertical member 10.

The rack 59 meshes with a gear 62 which is freely rotative on the stem 55. The gear 62 carries a spring urged pawl 63 which engages a ratchet 64 fixedly mounted on the gear 62 or drum 51. The arrangement is such that when the rack 59 is pressed downwards rotations will be transmitted to the drum 51 to wind the spring 52. However, when the rack 59 moves upwards the pawl 63 will merely idle over the ratchet 64.

Another gear 65 is fixedly mounted on the stem 55 by a pin 66. This gear 65 meshes with a gear 67 rotatively supported. A catch rod 68 is slidably mounted by standards 69 on the member 10. The catch rod 68 is capable of engaging the teeth of the gear 67 to hold the gear from turning. The catch rod 68 engages into a tubular portion 70 of a bracket 71 mounted on the rack 59. A spring 72 is mounted within the tubular portion 70 normally urging the catch rod 68 downwards.

The gear 67 meshes with a gear 73 freely mounted on the pintle 35 of the lever 33. A ratchet 74 is fixedly mounted to the lever 33 coaxial of the pintle 35. A spring urged pawl

75 is mounted upon the side of the gear 73 and engages the ratchet 74. The arrangement is such that the spring motor may drive the gear 73 and then the pawl 75 will drive the lever 33 downwards.

A cable 76 is connected with the pawl 75 and with a pivotally mounted lever 77. This pivotally mounted lever is pivotally supported intermediate of its ends on a bracket 78 mounted on the vertical member 10. An arm 79 projects from the tubular portion 70 of the arm 71 and is capable of striking the tail end of the lever 77 for pivoting the lever to release the pawl 75. In other respects this form of the invention is similar to the previous form and like parts are identified by like reference numerals.

In this form of the invention a pressure lever 11^a is shown to be pivotally held by the screws 32, so that the hat or other article may be pressed against the dry transfer over the heat unit 14 by a suitable pad 11^b when the handle 11^c of the pressure lever 11^a is pressed downwardly.

The operation of the device is as follows:

The lever 33 is in its down position where it is held because spring 50 is weaker than spring 52 and cannot wind the latter. When the knob 61 is depressed the rack 59 will move downwards and indirectly wind the spring 52. During the initial downward movement of the rack 59 the catch rod 68 moves down engaging the gear 67 and holding the gear stationary. This prevents the spring 52 from unwinding. When the rack 59 is in its completely down position the arm 79 will strike the lever 77 moving the pawl 75 and freeing the lever 33 which is immediately raised by the spring 50 to its top position in which it strikes the pins 49. When the article which receives the transfer is lifted off the knob 61 the rack 59 will move to its top position. During the initial portion of this motion the pawl 75 reengaged the ratchet 74. During the latter portion of this motion the catch rod 68 frees the gear 67. The spring 52 then transmits rotations to the gear 73 and through the medium of the pawl 75 and ratchet 74 drives the lever 33 to its down position. During this downward motion of the lever 33 the web 16 will advance. The device is now in its initial position with the operation ready to be repeated. In other respects the operation of this form of the invention is identical to the previous form.

The size, shape and material used of the various mechanism in the device may be changed as desired and may be covered by a suitable housing to give the device a smooth outside effect.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A machine for applying dry transfers in upright positions, comprising a vertical member over which various articles may be placed, a heat unit mounted across the top portion of said vertical member, guide means for guiding a web of dry transfer material up one side and over the top and down the other side of said vertical member, and means for advancing said web of dry transfer material in sections of pre-selected length, including a pivotally mounted lever

5 mounted upon the bottom portion of said vertical member and having a passage through which said web passes, a counter-pressure drum mounted beneath said lever, and a gripper jaw cooperative with said counter-pressure drum for gripping said web.

10 2. A machine for applying dry transfers in upright positions, comprising a vertical member over which various articles may be placed, a heat unit mounted across the top portion of said vertical member, guide means for guiding a web of dry transfer material up one side and over the top and down the other side of said vertical member, and means for advancing said web of dry transfer material in sections of pre-selected length, including a pivotally mounted lever mounted upon the bottom portion of said vertical member and having a passage through which said web passes, a counter-pressure drum mounted beneath said lever, and a gripper jaw cooperative with said counter-pressure drum for gripping said web, and toggle members mounted between said lever and a stationary part for advancing and retracting said gripper jaw.

15 3. A machine for applying dry transfers in upright positions, comprising a vertical member over which various articles may be placed, a heat unit mounted across the top portion of said vertical member, guide means for guiding a web of dry transfer material up one side and over the top and down the other side of said vertical member, and means for advancing said web of dry transfer material in sections of pre-selected length, including a pivotally mounted lever

20 mounted upon the bottom portion of said vertical member and having a passage through which said web passes, a counter-pressure drum mounted beneath said lever, and a gripper jaw cooperative with said counter-pressure drum for gripping said web, and toggle members mounted between said lever and a stationary part for advancing and retracting said gripper jaw.

25 4. A machine for applying dry transfers in upright positions, comprising a vertical member over which various articles may be placed, a heat unit mounted across the top portion of said vertical member, guide means for guiding a web of dry transfer material up one side and over the top and down the other side of said vertical member, and means for advancing said web of dry transfer material in sections of pre-selected length, including a pivotally mounted lever

30 mounted upon the bottom portion of said vertical member and having a passage through which said web passes, a counter-pressure drum mounted beneath said lever, and a gripper jaw cooperative with said counter-pressure drum for gripping said web, and toggle members mounted between said lever and a stationary part for advancing and retracting said gripper jaw, and an adjustably mounted stop for limiting downward motion of said lever.

35 5. A machine for applying dry transfers in upright positions, comprising a vertical member over which various articles may be placed, a heat unit mounted across the top portion of said vertical member, guide means for guiding a web of dry transfer material up one side and over the top and down the other side of said vertical member, and means for advancing said web of dry transfer material in sections of pre-selected length, including a pivotally mounted lever

40 mounted upon the bottom portion of said vertical member and having a passage through which said web passes, a counter-pressure drum mounted beneath said lever, and a gripper jaw cooperative with said counter-pressure drum for gripping said web, and toggle members mounted between said lever and a stationary part for advancing and retracting said gripper jaw, and an adjustably mounted stop for limiting downward motion of said lever.

45 6. A machine for applying dry transfers in upright positions, comprising a vertical member over which various articles may be placed, a heat unit mounted across the top portion of said vertical member, guide means for guiding a web of dry transfer material up one side and over the top and down the other side of said vertical member, and means for advancing said web of dry transfer material in sections of pre-selected length, including a pivotally mounted lever

50 mounted upon the bottom portion of said vertical member and having a passage through which said web passes, a counter-pressure drum mounted beneath said lever, and a gripper jaw cooperative with said counter-pressure drum for gripping said web, and toggle members mounted between said lever and a stationary part for advancing and retracting said gripper jaw, and an adjustably mounted stop for limiting downward motion of said lever.

55 7. A machine for applying dry transfers in upright positions, comprising a vertical member over which various articles may be placed, a heat unit mounted across the top portion of said vertical member, guide means for guiding a web of dry transfer material up one side and over the top and down the other side of said vertical member, and means for advancing said web of dry transfer material in sections of pre-selected length, including a pivotally mounted lever

60 mounted upon the bottom portion of said vertical member and having a passage through which said web passes, a counter-pressure drum mounted beneath said lever, and a gripper jaw cooperative with said counter-pressure drum for gripping said web, and toggle members mounted between said lever and a stationary part for advancing and retracting said gripper jaw, and an adjustably mounted stop for limiting downward motion of said lever, resilient means normally urging said lever upwards.

65 8. A machine for applying dry transfers in upright positions, comprising a vertical member over which various articles may be placed, a heat unit mounted across the top portion of said vertical member, guide means for guiding a web of dry transfer material up one side and over the top and down the other side of said vertical member, and means for advancing said web of dry transfer material in sections of pre-selected length, including a pivotally mounted lever

mounted upon the bottom portion of said vertical member and having a passage through which said web passes, a counter-pressure drum mounted beneath said lever, and a gripper jaw cooperative with said counter-pressure drum for gripping said web, and toggle members mounted between said lever and a stationary part for advancing and retracting said gripper jaw, and an adjustably mounted stop for limiting downward motion of said lever, resilient means normally urging said lever upwards, and a spring motor for moving said lever downwards, said spring motor including a depressible rack for winding the same.

6. A machine for applying dry transfers in upright positions, comprising a vertical member over which various articles may be placed, a heat unit mounted across the top portion of said vertical member, guide means for guiding a web of dry transfer material up one side and over the top and down the other side of said vertical member, and means for advancing said web of dry transfer material in sections of pre-selected length, including a pivotally mounted lever mounted upon the bottom portion of said vertical member and having a passage through which said web passes, a counter-pressure drum mounted beneath said lever, and a gripper jaw cooperative with said counter-pressure drum for gripping said web, and toggle members mounted between said lever and a stationary part for advancing and retracting said gripper jaw, and an adjustably mounted stop for limiting downward motion of said lever, resilient means normally urging said lever upwards, and a spring motor for moving said lever downwards, said spring motor including a depressible rack for winding the same, latching means for holding the spring motor wound, and means for releasing said latch-

ing means to cause said spring motor to unwind and move said lever downwards.

7. A machine for applying transfers, comprising a member over which various articles may be placed, guide means for guiding a web of transfer material along one side across the face thereof and along the other side of said member, a lever pivotally mounted on said member to have its free end adjacent the free end of said web and formed with a passage through which the free end of said web passes, a counter-pressure drum mounted on the underside of said lever and engaging one side of said web, and a gripper jaw mounted on the underside of said lever and engaging the other side of said web to cooperate with said drum to grip and advance said web when said lever is pushed downwards.

8. A machine for applying transfers, comprising a member over which various articles may be placed, guide means for guiding a web of transfer material along one side across the face thereof and along the other side of said member, a lever pivotally mounted on said member to have its free end adjacent the free end of said web and formed with a passage through which the free end of said web passes, a counter-pressure drum mounted on the underside of said lever and engaging one side of said web, and a gripper jaw mounted on the underside of said lever and engaging the other side of said web to cooperate with said drum to grip and advance said web when said lever is pushed downwards and means for moving said gripper jaw towards said counter-pressure drum on the down stroke of said lever to grip said web and for moving said gripper jaw away from said counter-pressure drum on the up stroke of said lever to free the end of said web after being advanced.

EDWARD E. ZISKIND.
